SUPERHEATER

Heinrich Peperkorn, Friedrich Wempe, and Otto H. Hartmann, Cassel-Wilhelmsche, Germany, assignors to The Superheater Company, New York, N. Y.

Application October 6, 1931, Serial No. 567,203,
and in Germany October 28, 1930

5 Claims. (Cl. 122—462)

The invention relates to flue superheaters for marine boilers and particularly to such cases in which the return ends of the superheater loops extend freely into the return or combustion chamber to obtain a higher degree of superheat. In superheaters of this class it was customary right from the outset not to extend into the combustion chamber the return portions of all of the superheater elements lying in the flues but only those lying in the two or three rows nearest to the walls. This was done in order to leave as unobstructed as possible the interior of the return chamber so that there would be a free space between the ends extending into the chamber at the sides and top where the flame could develop freely and from which the ends of the flues could be readily examined and repaired. Of course this advantage brought about a diminution of the amount of superheater surface. The present invention has for its object to retain the advantages of the old arrangements and not only to make up for the loss of superheating surface but to increase the superheat further. A superheater in accordance with the present invention has the ends of the superheater loops extending into the return chamber act as radiant superheater surface in such a manner that only one row of tubes along the top and sides are equipped with elongated superheater loops and that the superheating surface of these units is increased in the return chamber. This increase is advantageously brought about either by having the superheater loops extend as simple loops into the return chamber, but to have these portions within the return chamber provided with ribs welded to them in a known way in order to increase the heat absorbing surface or secondly, by giving the superheater loops in the flues along the walls the form within the return chamber of loops bent back on themselves. In both cases the convection heated surface of all of the superheater elements in the flues is increased by an augmented radiant surface along the side and top of the return chamber, whereas on the other hand all of the remaining area of the flue sheet is accessible from the return chamber. In order to support the portions of the loops extending into the return chamber, there are advantageously used angles secured to the roof and side walls and formed with properly shaped slots. The flow of the steam which is to be superheated may be such that it traverses successively those elements which end within the flues and then those arranged along the walls and roof and which extend into the return chamber. During firing up the cooling steam which is sent through the superheater for the purpose of protecting it flows through all of the superheater elements although this is usually not required for those which end within the flues. However, to minimize the amount of cooling steam required in this connection, the arrangement is most advantageously such that the superheater loops which extend into the return chamber are connected as separate groups to the interstage steam header so as to form a preliminary superheater or a secondary superheater during the firing up of the boiler which can be cooled independently of the rest of the superheater. With such an arrangement the cooling steam used during firing up periods will be sent only through the superheater elements having a radiant surface located in the flues along the roof and side walls.

The drawings show several forms of the invention by way of illustration. Fig. 1 shows the return or combustion chamber of a marine return tubular boiler together with the flues opening into the end, with a superheater of the most advantageous form of the invention, the increased radiant surface being formed by means of ribs welded to the tubes. Fig. 2 is a cross section on line 2—2 of Fig. 1. Fig. 3 is a cross section on line 3—3 of Fig. 1. Fig. 4 shows a variation in which the increase in the radiant heating surface is brought about by bending the elements back on themselves. Fig. 5 is a cross section on line 5—5 of Fig. 4. Figs. 6, 7 and 8 show an advantageous sequence of steam flow wherein the extended superheater units of the wall and roof flues are connected as separate groups to the superheater headers to form a unitary superheater; Fig. 6 showing a fragmentary end elevation of the flue sheet, while Fig. 7 shows at the left a section on the broken line 7—7 and at the right a section on the broken line 7a—7a of Fig. 6; Fig. 8 showing a vertical section through the boiler on line 8—8 of Fig. 6. Fig. 9 shows a partial section through the combustion chamber with the provisions for supporting the extended return portion of the superheater elements.

In the drawings, 2 are the return or combustion chambers of the return tubular boiler, into which open the flues 3 most of which are occupied by superheater units. In each chamber all of the inner flues are equipped with superheater units 4 of the usual type ending within the flues. A similar row along each of the side walls and the roof of each of the return chambers 2 is occu-

75

110

plied with superheater elements which are extended into the vicinity of the rear wall, this extension being, in accordance with the invention, shaped so that an increased radiant superheating surface is presented.

In Fig. 1 the extended superheater loops 5 are for this purpose provided with ribs 6 welded to them, these ribs extending from the flues through the return chamber. As will be seen from Fig. 1, 10 the over-all width of each element is kept such that it is not greater than the diameter of the flue 3. In the case of the superheater loops adjacent to the roof these elements extend through to the rear wall without any twist, where- 15 as the superheater loops adjacent to the side walls and equipped with the ribs the loops are twisted through 90° as is seen from Fig. 2. Both the loops along the roof and along the side therefore present their broad side to the flame. In 20 the form of Fig. 4, the return portions of the superheater elements 8 which occupy the top and side flues are bent back on themselves within the return chamber so that each loop has three instead of one return bend. At the same time, 25 the portions of the superheater loops which are bent back are twisted through 45° in order to present the greatest possible surface to the flame. Such an arrangement of the superheater results in considerably increased superheat on account 30 of the radiant surface that has been added, while it yet retains the advantage that the largest possible portion of the flue sheet in the return chamber remains accessible. If the desired superheat cannot be reached with this arrangement in any 35 particular case, the superheater elements in the flues adjacent to those next to the wall and roof and which normally end within the flues, might be extended into the return or combustion chamber by greater or shorter distance as indicated 40 in dotted lines in Fig. 7. On the other hand, if the form of the invention shown in Figs. 1 and 4 results in too high a degree of superheat, this can be lowered to the desired point either by letting all the end pieces of the superheater elements 45 forming a radiant heating surface extend into the return chamber a shorter distance, or by re-stricting the extension to only a part of the super-heater elements occupying the flues adjacent to the roof and walls. In order to secure the ex- 50 tended superheater ends in their position, there are advantageously used supporting members made of angle irons 10 which are fastened to the roof and side walls of the return chambers and provided with slots 11 corresponding to the out- 55 line of the superheater elements. An advantage- 60 ous flow sequence of the steam to be super-heated can be gathered from Figs. 6 to 8. The boiler in this example is a three-flow boiler and as usual in such a case there are provided two groups of superheater headers placed in the vertical position in front of the front flue sheet. Each group consists in the form illustrated of 65 three chambers, one long chamber 14 lying next to the flue sheet, an angular chamber 15 and a short chamber 16. From the latter two extend the distribution headers 17 and 18 to which are 70 attached the lateral superheater elements 5, and distributing chambers 19 and 20 to which are at- 75 tached the superheater elements 5 lying adjacent to the roof of the return chamber. The steam to be superheated flows in the first place into the saturated steam chamber 14 to be ini- 80 tially superheated in the superheater elements which are not extended into the combustion chamber and to flow thence into the intermediate

chamber 15. From here the initially superheated steam flows for final superheating through the elements which are extended into the combustion chamber and which are attached to the headers 17, 18, 19 and 20, to be finally delivered to the superheated steam chamber 16 from which the steam flows in a highly superheated condition to the engine. Of course the group arrangement could also be reversed so that the group forming the radiant superheater forms the initial superheater and the elements which are not extended into the combustion chamber form the final superheater. However, the former sequence is preferable. The intermediate chamber 15 and short chamber 16 have connections 21 and 22 through which cooling steam is supplied during firing up, suitable valves being of course provided in the supply line and drain. In this manner during firing up the cooling steam is sent through the intermediate chamber 15 and the extended elements of the radiant superheater into the short chamber 16 from which it is allowed to escape. Cooling steam can also through the connections on the intermediate headers 15 reach the elements which are not extended, without, how- 90 ever, flowing through them. In this manner cooling steam for cooling the superheater during firing up is saved. In ordinary cases the extended superheater portions of the radiant super- 95 heater can be made of ordinary steel. If re- 100 quired, however, these portions can be made out of special heat resisting material such as molyb- 105 denum steel.

What I claim is:

1. In apparatus of the class described, the combination of a combustion chamber, a group of vertically alined flues leading from the chamber, tubular superheater elements arranged in the flues, each flue containing only one loop extending into the flue from the end remote from the combustion chamber and comprising two horizontally alined pipes, the loops terminating at a point short of the combustion chamber except those loops in the rows of flues immediately adjacent to the walls of the combustion chamber, the loops in said rows extending into the combustion chamber and the pipe lengths constituting them all being in planes parallel respectively to the corresponding combustion chamber wall.

2. In apparatus of the class described, the combination of a combustion chamber, a group of vertically alined flues leading from the chamber, tubular superheater elements arranged in the flues, each flue containing only one loop extending into the flue from the end opposite the combustion chamber and comprising two horizontally alined pipes, the loops in the outside vertical row on each side being extended into the combustion chamber and there each having its constituent pipe lengths arranged to lie within the projected area of the respective flues and to extend vertically over a materially greater width than the diameter of a single pipe, thereby exposing a materially increased surface to radiation from the flame in the combustion chamber.

3. In apparatus of the class described, the combination of a combustion chamber, a group of vertically alined flues leading from the chamber, tubular superheater elements arranged in the flues, each flue containing only one loop extending into the flue from the end opposite the combustion chamber and comprising two horizontally alined pipes, the loops in the outside vertical row on each side being extended into the combustion chamber and there each having its two constitu-

ent pipe lengths arranged vertically one over the other thereby exposing an increased surface to radiation from the flame in the combustion chamber.

5 4. In apparatus of the class described, the combination of a combustion chamber, a group of flues leading from it, tubular superheater elements arranged in the flues, some of said elements terminating short of the combustion chamber and others extending into it, the latter being connected to form a separate group which may be separately cooled during firing up of the boiler.

10 5. Flue tube superheater for return tube boilers having return portions which in part extend freely into the return or combustion chamber, characterized by the fact that in order to get

the full benefit of the portions extending into the return chamber as radiant heat absorbing surface, only one row of flues in each of the flues adjacent to the top and side walls are occupied with extended superheater elements having an increased superheating surface inside of the return chamber, the superheater elements in said flues adjacent to the top and side walls being connected as a separate group to an intermediate steam header chamber so as to form a separate initial or final superheater which may be cooled by itself during firing up of the boiler.
